UNITED STATES PATENT OFFICE

94,470

DESIGN FOR A VERNIER DIAL

Samuel S. Egert, Brooklyn, N. Y.

Application April 20, 1934, Serial No. 51,469

Term of patent 3½ years

To all whom it may concern:

Be it known that that I, Samuel S. Egert, a citizen of the United States, residing at Brooklyn, in the county of Kings and State of New York, have invented a new, original, and ornamental Design for Vernier Dials, of which the following is a specification, reference being had to the accompanying drawing, forming part hereof.

Figure 1 is a face view of a vernier dial show-

ing my new design; and Fig. 2 is a central horizontal section looking downwardly, the axial portion being shown partly broken away.

I claim:

The ornamental design for a vernier dial as shown.

In testimony whereof he affixes his signature.

SAMUEL S. EGERT.
